The ornamental design for a RV side camera with marker light, as shown and described.

DESCRIPTION

FIG. 1 is a top, front and right side perspective view of a RV side camera with marker light showing my new design; FIG. 2 is a bottom, rear and left side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of portion 9 shown in FIG. 1;

FIG. 10 is an enlarged view of portion 10 shown in FIG. 3;

FIG. 11 is an enlarged view of portion 11 shown in FIG. 3; and,

FIG. 12 is an enlarged view of portion 12 shown in FIG. 5. The broken lines shown in the drawings are included for the purpose of illustrating portions of the RV side camera with marker light that form no part of the claimed design. In addition, the dot-dash broken lines in FIGS. 1, 3, 5, and 9–12 depict the boundaries of the enlargements that form no part of the claimed design.
